UNITED STATES PATENT OFFICE.

EUGENE H. PHILBRICK, OF ROCKLAND, MAINE.

ATTACHMENT FOR OILERS.

1,101,327.

Specification of Letters Patent. Patented June 23, 1914.

Application filed April 18, 1913. Serial No. 762,270.

To all whom it may concern:

Be it known that I, EUGENE H. PHILBRICK, a citizen of the United States, residing at Rockland, in the county of Knox and 5 State of Maine, have invented new and useful Improvements in Attachments for Oilers, of which the following is a specification.

This invention relates to a flash light attachment for hand oilers or the like, and it 10 is the chief object thereof to provide a flash light device which is mounted upon the handle of the oiler and which is adapted to direct its rays of light upon the nozzle of the oiler so that the oil openings in bearings 15 or lubricators may be illuminated during the act of filling the same with oil. In oiling overhead shaft bearings in a dark engine room, it is often necessary, in using the ordinary oiler, to mount a ladder with the oiler 20 in one hand and a lantern or torch in the other, so that the oiling may be accomplished accurately and without wasting quantities of the lubricant. This operation is hazardous 25 and troublesome at best, as should be readily apparent. In using my attachment for oilers, the task of oiling bearings in dark and secluded spots is greatly facilitated in many respects.

A further object of the invention is to 30 provide a special handle for oilers, to which the flash light device may be readily attached or may be readily removed therefrom and which is adapted to maintain the flash light device at the proper angle with respect to the discharge spout, the said flash 35 light device serving during such use as a part of the handle so that it may be included in the grasp of the operator and is in a position to be manipulated conveniently in 40 flashing the light.

The invention consists in the features of construction, combination, and arrangement of parts, hereinafter fully described and claimed, reference being had to the accompanying drawings, in which:

Figure 1 is a side elevation of an engine oiler having the flash light device applied thereto; Fig. 2 is a transverse sectional view taken through the handle and flash light device; and Fig. 3 is a fragmentary top plan view of the oiler handle, the flash light device being removed therefrom.

In the drawing, the numeral 1 designates the body of an oiler which is provided with 55 the usual discharge spout 2 and has a

specially constructed handle 3 formed thereon, whose grip portion 4 is disposed at such an angle that the flash light device 5 detachably secured thereto is adapted to direct the rays of light produced therein 60 through its lens 6 on the discharge end of the nozzle or spout 2 when the actuating button 7 is pressed. The flash light device may be of any ordinary well known type, but is preferably round in transverse section, and 65 is provided with a longitudinally extending rib 8 having the lateral flanges 9 for slidable reception within the guide groove 10 formed between the indent flanges 11 of the handle grip. The rib 8 and the handle 70 groove are tapered toward the outer portion of the handle grip, so that means is provided for securely retaining the flash light device in applied position, wherein it is co-extensive with the grip portion of the handle 75 and is included in the operator's grasp so that the push button 7 will be in a convenient position to be operated by the hand supporting the oiler.

From the foregoing description taken in 80 connection with the accompanying drawing, it should be seen that I have provided a very useful construction of oiler and an attachment therefor which should prove of great service to engineers and machinists and 85 wherein the flash light attachment may be readily detached from the handle of the oiler for the purpose of replacement or repair of its parts. It is to be understood, however, that I do not necessarily limit myself to the exact details of construction described and shown, but that minor changes 90 in the details of construction may be resorted to in practice without departing from the scope of the invention. 95

Having thus described my invention, what I claim is:

The combination with an oiler having a discharge spout, of a handle therefor including an inclined grip portion provided 100 with a downwardly tapering groove, and a flash light device having a tapered rib adapted to be received within the said groove.

In testimony whereof I affix my signature 105 in presence of two witnesses.

EUGENE H. PHILBRICK.
